US00D852354S

(12) **United States Design Patent** (10) **Patent No.:** **US D852,354 S**
Wrangmark et al. (45) **Date of Patent:** **** Jun. 25, 2019**

(54) **FASTENER FOR MEDICAL TUBES LINES AND CABLES**

(71) Applicant: **MEDOW AB**, Lund (SE)

(72) Inventors: **Linn Wrangmark**, Lund (SE); **Frida McCabe**, Lund (SE)

(73) Assignee: **Medow, AB**, Lund (SE)

(**) Term: **15 Years**

(21) Appl. No.: **35/504,462**

(22) Filed: **Aug. 15, 2017**

(80) **Hague Agreement Data**

Int. Filing Date: **Aug. 15, 2017**

Int. Reg. No.: **DM/098771**

Int. Reg. Date: **Aug. 15, 2017**

Int. Reg. Pub. Date: **Feb. 16, 2018**

(30) **Foreign Application Priority Data**

Feb. 24, 2017 (EM) 003764901-0002

(51) **LOC (11) Cl.** **24-02**

(52) **U.S. Cl.**

USPC **D24/128**; D13/155; D8/356

(58) **Field of Classification Search**
